UNITED STATES PATENT OFFICE.

HESPERE SEREBRIAKOFF, OF PARIS, FRANCE.

SLOW-COMBUSTION STOVE.

SPECIFICATION forming part of Letters Patent No. 510,714, dated December 12, 1893.

Application filed June 12, 1893. Serial No. 477,346. (No model.) Patented in France October 3, 1892, No. 224,694; in Belgium October 3, 1892, No. 101,585, and in England October 18, 1892, No. 18,636.

To all whom it may concern:

Be it known that I, HESPERE SEREBRIAKOFF, a subject of the Emperor of Russia, and a resident of Paris, in the Department of the 5 Seine, France, have invented a new and useful Improvement in Slow-Combustion Stoves, (for which I have obtained patents in France, No. 224,694, dated October 3, 1892; in Belgium, No. 101,585, dated October 3, 1892, and in 10 England, No. 18,636, dated October 18, 1892,) of which the following is a specification.

This invention relates to an improved economical and slow combustion stove which is capable of being arranged as a fixture, or may 15 be mounted upon wheels, so as to be portable, and readily moved about from one room to another.

In order that the invention may be readily understood I have shown, by way of example, 20 in the accompanying drawings, a portable stove constructed in accordance therewith.

Figure 1 is an axial section of the stove taken on the line A, B, of Figs. 2 and 3, and Figs. 2 and 3 are transverse sections of the 25 same taken respectively on the lines C, D, and E, F, of Fig. 1.

This stove consists of the following parts, viz: two vertical concentric cylinders of circular or polygonal section, and composed of 30 asbestos iron, the composition of which material will be hereinafter indicated; a fire place composed of refractory bricks; an iron fuel reservoir lined with refractory clay; an ash pan or tray having a regulator; a pipe 35 having a regulator.

The cylinders 1 and 2 are made of asbestos iron; that is to say they are each composed of three superposed layers, an inner layer of iron and two outer layers of asbestos, the distance between the two cylinders being at least 40 one-fourth inch.

The fire place 3 is located within the cylinder 2, and is composed of several superposed annular bricks. Its lower portion consists of 45 an annular refractory piece or block 4, the inner walls of which are formed as a truncated cone, and provided with lateral holes or passages 5, 5, arranged at different levels, and in various directions. A space of at least 50 one twenty-fourth of an inch is left between this annular piece and the inner wall of the

cylinder 2. This first ring 4 is surmounted by a second ring 6, which fits closely against the inner wall of the cylinder 2, and is formed, at its lower part, with a deep channel 7 having 55 its upper side pierced with vertical holes 8, 8. The succeeding annular bricks 9, 9, which are thinner, are situated one above the other, and the wall of the last or uppermost one is reduced in thickness, on one side, and 60 cut away on the other. A brick or asbestos iron partition or diaphragm caps the series.

The inner cylinder 2 is provided with a series of holes 11 on a level with, and in front of, the cut away portion of the last or uppermost brick, said holes enabling the gases to 65 enter the space between the two cylinders 1, 2, by following the course indicated by the arrows.

The fuel reservoir 12 is an iron cylinder 70 lined with refractory clay or bricks and descends as far as the annular piece, block, or brick 6.

The two cylinders 1, 2, are cutaway at their lower parts for the reception of the ash-pan 75 13. The outer cylinder receives the pipe 14 through which the gases of combustion escape. These two cylinders are connected and held together by means of two iron or steel plates 15 and 16 which are lined with a layer 80 of asbestos and clay. The upper plate 15 is provided with a central hole which is closed by means of a cover 17. Wheels 18 may be fitted to the lower plate.

The ash pan 13 consists of an iron or asbestos case, which, when in place, hermetically closes the front opening, and it is furnished with a regulator 19 on its outer face to enable the entry of air to be regulated. The pipe 14 is also furnished with a regulator 90 20, in the form of a valve, or butterfly, for regulating the exit of the gases of combustion.

A cast iron grate 21, is situated in the interior and at the lower part of the first or 95 lowermost brick ring 4.

The cover 22, is of marble or metal.

Combustion is effected in the following manner: A quantity of live coal is introduced into the fireplace, the reservoir is filled 100 with fuel, and the stove is closed by the screw cover 17. Air enters through the openings

- in the regulator 19, into the ash pan, passes through the grate, and through the holes or 5 passages 5 into the fireplace, where it supports combustion. The gases of combustion filling the circular channel 7, rise up through the holes 8, pass through the holes 11 into the space between the two cylinders, which they fill, and finally escape through the pipe 14 to the chimney.
10. What I claim, and desire to secure by Letters Patent of the United States, is—
1. In a slow combustion stove, a fire-place formed of superposed sections, or rings, of fire-clay, an annular passage communicating with the upper part of said fire-place, a hollow casing formed of two concentric cylinders of asbestos iron arranged outside of said annular passage and fire-place, the inner cylinder having passages for the escape of the gases of combustion from the upper end of said annular passage into the hollow casing, and a pipe to carry off the products of combustion, substantially as described.
  2. In a slow combustion stove in which the fireplace is built up of superposed fireclay sections, or rings, the construction of the lowermost one with its upper part enlarged on its interior, and formed with lateral holes or passages, and the section or ring immediately above it formed with a circular groove or channel having vertical holes or perforations through which the gases of combustion pass from the grate to reach the space between the double casing, substantially as described and 35 shown.
  3. In a slow combustion stove, the combination with the fire-place built up of superposed fire-clay sections or rings, and surrounded by a double casing of asbestos iron, of a centrally located fuel reservoir adapted to be closed with a tight fitting cover and passing through partitions situated above the fire place, said fuel reservoir being so disposed as to leave a space for the ascending gases of combustion to reach openings leading into the space between the casings and, after circulating therein, to reach the chimney, substantially as described and shown.
  4. In a slow combustion stove, a fire-place formed of superposed sections or rings of fire-clay, an annular passage for the products of combustion having its lower end in communication with the fire-place, a surrounding hollow casing formed of two concentric cylinders of asbestos iron, the inner cylinder provided with openings to permit the passage of the products of combustion from the top of the annular passage into the hollow casing, a tight-fitting ash-pan having a regulator for controlling the entrance air, and a pipe to carry off the products of combustion, substantially as described.

In testimony whereof I have signed this specification in the presence of two subscribing witnesses.

HESPERE SEREBRIAKOFF.
